WELT BAR FOR FULL FASHIONED HOSIERY MACHINES

Alfred Percy Saunders, Leicester, England, assignor to Wildt and Company Limited, Leicester, England, a British company

Application March 7, 1951, Serial No. 214,334

Claims priority, application Great Britain March 7, 1950

8 Claims. (Cl. 66—96)

1

This invention appertains to full fashioned hosiery machines furnished with spring beard needles, and has reference particularly to such machines adapted to produce fully fashioned blanks, e. g. stocking blanks having welts, i. e. top portions consisting of double fabric.

The invention, moreover, relates to the welt instruments provided in such machines for picking up from the needles and temporarily retaining the initial course of loops at the commencement of knitting a blank and for transferring the aforesaid loops back to the needles after turning of the welt fabric.

Welt hooks are customarily provided for picking up and retaining the initial course of loops, and these hooks are combined or closely associated with loop transferring means for the purpose specified.

Heretofore, after the loops of the initial course have been transferred back to the needles, it has almost invariably been necessary so to actuate the welt hook bar, either manually or automatically, as to effect disengagement of the welt hooks from the said loops. Naturally this is an operation requiring care in its performance and, however carefully done, there is a tendency for the hooks as they are withdrawn to damage at least some of the initial loops.

The primary object of the present invention is to provide, in or for a full fashioned hosiery machine, a welt bar of improved form which is so constructed and operable as to enable the welt hooks to be neutralized either preparatory to or during the transfer of initial loops, thereby ensuring a smooth, uninterrupted passage of the loops from the loop transferring means back to the needles, and obviating the necessity for subsequent disengagement of the hooks from the said loops with the consequent risk of damage thereto.

A further object of the invention is to provide, in a welt bar, improved loop transferring means adapted to house the welt hooks when neutralized and also to facilitate the transference of loops of the initial course back to the needles, as will be hereinafter described.

The improved welt bar constituting this invention is furnished with a series of hook-shaped elements (hereinafter for convenience referred to as "welt instruments") for picking up an ini-

2

tial course of loops as aforesaid, and also a corresponding separate series of loops transferring instruments, the said welt instruments being movable relatively to the loop transferring instruments and withdrawable to safe idle positions clear of the operative ends of the latter.

According to an important feature of the invention the loop transferring instruments may advantageously be of hollow form and thereby adapted to house the corresponding welt instruments and cover the hooks whenever the said instruments are moved to safe idle positions clear of the operative ends of the loop transferring instruments. The operative ends of the loop transferring instruments, being hollow, are thus adapted to receive and cover or sheathe the needle hooks suchwise as to facilitate a smooth passage of loops from the loop transferring instruments back to the needles. It will therefore be appreciated that when the welt instruments are fully withdrawn into the loop transferring instruments and the welt bar is moved to enable the loop transferring instruments and the needles to be brought into alignment preparatory to a transfer of loops, the needles will then be free to be positioned within the hollow operative ends of the loop transferring instruments and to receive initial loops from the latter without risk of contacting the welt instruments.

A specific example of the improved welt bar embodying the foregoing and other features of the invention will now be described with reference to the accompanying drawings, wherein:

Figure 1 is a view partly in vertical section, showing one end of the welt bar in relation to the knitting instrumentalities of the machine, and with a welt instrument projected to receive from the appropriate needle a loop of the initial course,

Figure 2 is a similar view to Figure 1 but showing the composite welt bar as it appears when moving bodily away from the knitting instrumentalities to cause the hooked welt instruments to apply tension to the welt fabric before the latter is turned,

Figure 3 is a further similar view showing the welt bar changing direction to position the initial course of loops onto the pointed ends of the loop transferring instruments and also to maintain the tension on the fabric, the hooked welt instru-

ments being free at this stage to be withdrawn to their inoperative positions.

Figure 4 is a still further similar view showing the composite welt bar in the course of being bodily elevated to a position in which the initial course of loops can be transferred back to the needles.

Figure 5 shows the welt bar fully elevated with the needle hook covered by the operative end of the hollow loop transferring instrument in which latter the corresponding and now inoperative welt instrument is housed.

Figure 6 is a detail perspective view of one of the hooked welt instruments per se.

Figure 7 is a detail perspective view of one of the hollow loop transferring instruments per se, and

Figure 8 is a plan view of the composite welt bar, showing a few only of the welt and loop transferring instruments.

Like parts are designated by similar reference characters throughout the drawings.

Each of the welt instruments 1 is formed with a relatively fine hook 2 of a reduced section, and has a stem 3 which is wider and thicker than the said hook. Between the hook 2 and the stem 3, however, there is an intermediate tapered portion 4. The back edge of the stem 3 is recessed at 5 for a purpose hereinafter to be explained. At the end of the instrument 1 remote from the hook 2, there is a down-turned locating tail 6.

The hooked welt instruments 1 are fixedly mounted in an appropriately cut portion 7 of a bar 8, and are located by engagement of their tails 6 in holes 9 drilled in the said bar. This is, of course, a method well known for locating bearded needles. When the full complement of welt instruments 1 has been assembled in the bar 8, the instruments are secured by a holding bar 10 which is locked to the bar by screws 11 screwed into tapped holes 12 formed in the bar at regularly spaced intervals therealong (see Figure 8). The bars 8 and 10, together with the welt instruments 1, accordingly constitute a unit which may be regarded as the hooked welt bar.

As shown more clearly in Figure 7, each of the loop transferring instruments 13 in this example is quite separate from the corresponding hooked welt instrument 1 and is generally of U-section hollow form from end to end. Each instrument 13 therefore has upstanding parallel side walls 14 merging into a rounded bottom and is thereby adapted entirely to enclose the corresponding welt instrument 1 when the latter is fully retracted thereinto. Thus, again referring to Figure 7, each channel-shaped loop transferring instrument has a point 15 at its leading end, transferring shoulders 16 at short distance behind the said point, and locating means constituted by recesses 17 formed in the upper edges of the parallel side walls 14 of the instrument. The rear end of the instrument 13 is, of course, entirely open to permit of longitudinal movement therethrough of the corresponding welt instrument 1.

The loop transferring instruments 13 are carried in a second bar 18 having grooves 19 cut therein to receive them. To secure the instruments 13 in the bar 18 there is provided an upper-securing plate 20 which has formed on its underside a locating tenon 21 adapted to engage in the aforementioned recesses 17 for the purpose of aligning the assembled loop transferring instruments. The rear marginal edge portions of the bar 18 and of the associated securing plate 20 are secured together by means of screws 21a

with a spacing bar 22 interposed between them. The screwed portions of the screws 21a are located in tapped holes formed at regularly spaced intervals along the plate 20. As will be appreciated from a consideration of each of Figures 1-5, the structure comprising the bar 18, the upper securing plate 20 and the interposed spacing bar 22 constitutes, in effect, an outer hollow bar for the loop transferring instruments 13, the space 23 within the said bar serving not only to accommodate, but also to permit of relative sliding movement back and forth of, the hooked welt bar composed of the two bars 8 and 10. When the hooked welt bar is drawn right back into contact with the spacing bar 22, the hooks 2 are located to the rear of the points 15 of the loop transferring instruments 13. As shown in Figure 8, projections 24 are provided at the opposite ends of the bars 8 and 10, thereby enabling the latter to be further locked together, by screws 25, and providing a ready means of operating the bars—either manually or automatically.

Referring now to Figure 1, the composite welt bar is shown moved towards the needles 26, with the welt instruments 1 fully projected. Consequently, when the initial loops such as L are drawn over the sinkers 27, movement of the needles downward conjointly with retraction of the sinkers will cause the said loops to land onto the stems of the welt instruments 1. As knitting proceeds, the composite welt bar is moved away from the needles 26, with the instruments 1 still projected, so that the welt fabric F is tensioned as shown in Figure 2. When the fabric F is turned, either manually or automatically, as depicted in Figure 3, a rod 28 is inserted and, by an appropriate change in direction of the composite welt bar, the initial loops L are drawn onto the pointed ends of the loop transferring instruments 13 and arrested by the transfer shoulders 16. At this stage the bars 8 and 10 together constituting the hooked welt bar, can conveniently be drawn back up to the spacing bar 22 so as to position the hooks 2 entirely within the hollow loop transferring instruments safely behind the points 15 thereof. As knitting continues, the composite welt bar is moved forward and elevated, in the manner depicted in Figure 4, so as ultimately to be in a position to receive the needle hooks 26a upon completion of the welt fabric F and to enable the initial loops L to be returned to the needles to close the welt. In Figure 5 the needle hooks 26a are shown within the loop transferring instruments 13 and the welt instruments 1 are clear of the needle heads. When subsequently the welt fabric F is moved from position a on the instruments 13 to the position b on the stems of the needles 26, the movement of loops L is smooth and uninterrupted owing to the needle heads being sheathed by the instruments 13.

Referring to Figures 6 and 7, the intermediate tapered portion 4 between the hook 2 and the stem 3 of each welt instrument 1 is adapted to lift an initial loop L to a position suitable for landing onto the transfer shelf 29 of the corresponding loop transferring instrument 13 (Figure 7). As will be appreciated, the recess 5 in the back of each welt instrument 1 is provided to receive the point 15 of the corresponding instrument 13. The hollow pointed end of each loop transferring instrument is adapted to accommodate both a hook 2 and a needle hook 26a without these fouling one another.

Although for the sake of convenience in Fig-

ure 8, a few only of the instruments 1 and 13 are shown assembled in the end portions of the bars 8 and 10 and 18 respectively, it is, of course, to be understood that the said bars are equipped with a full complement of instruments, according to requirements.

At 30 are indicated additional locking screws for gripping the loop transferring instruments 13 when assembled between the bar 18 and the securing plate 30.

What we claim then is:

1. For a full fashioned hosiery machine, a welt bar provided with a series of hooked welt instruments, and a corresponding separate series of one-piece channel-shaped loop transferring instruments adapted to house the welt instruments, the welt instruments being movable relatively to the loop transferring instruments and withdrawable into the latter to positions clear of the open operative ends thereof, the hooks of the welt instruments, when so withdrawn, being safely covered by the channel-shaped bodies of the loop transferring instruments, and the operative ends of the loop transferring instruments being adapted to receive the hooks and sheath the heads of needles to which loops are to be transferred.

2. For a full fashioned hosiery machine, a composite welt bar device comprising, in combination, a bar, a series of hooked welt instruments fitted in said bar, an associated second bar, and a corresponding separate series of one-piece channel-shaped loop transferring instruments fitted in said second bar, the first mentioned bar being movable relatively to the second mentioned bar from one position in which the welt instruments are fully projected with their hooks extending in advance of the open operative ends of the loop transferring instruments to another position in which the said hooks are withdrawn into the loop transferring instruments to inoperative positions behind the said operative ends thereof, and vice versa, and the said open operative ends of the loop transferring instruments being adapted to receive the hooks and sheath the heads of needles to which loops are to be transferred.

3. A welt bar device according to claim 2, wherein the channel-shaped loop transferring instruments each have permanently separated sides, a pointed operative end, and shoulders located behind the pointed end.

4. For a full fashioned hosiery machine, a composite welt bar device comprising, in combination, a bar having formed therein slots and a longitudinal series of holes, a series of welt instruments each formed with a relatively fine hook and a stem which is wider than the said hook and which has a down-turned tail, the said instruments being mounted in the slots in the bar and located in the latter by engagement of their down-turned tails in the aforesaid holes, a holding bar locked to the first mentioned bar to secure the welt instruments therein, the two bars together with the welt instruments constituting a unitary "hooked welt bar," an associated third bar having grooves therein, a corresponding separate series of loop transferring instruments fitted in the said grooves, each of said loop transferring instruments being of single-piece U-section hollow form from end to end and having a point at its leading end, transfer shoulders behind the said point and recesses formed in the edges of its side walls, a plate serving to secure the loop transferring instruments in the said third bar and having thereon a locating formation engaged in the aforesaid recesses, and a spacing bar interposed between and serving to connect the third bar and the securing plate so as to produce a hollow structure having a space therein accommodating and permitting relative movement back and forth of the hooked welt bar, the welt instruments being housed within the hollow loop transferring instruments, the hooked welt bar being movable from an advanced position in which the welt instruments are fully projected with their hooks extending in front of the points of the

thereof, and vice versa, and the said open operative ends of the loop transferring instruments being adapted to receive the hooks and sheath the heads of needles to which loops are to be transferred.

5. For a full fashioned hosiery machine, a welt bar device comprising, in combination, a bar, a series of hooked welt instruments fitted in said bar, an associated second bar having grooves therein, a corresponding separate series of loop transferring instruments fitted in the said grooves, each of said loop transferring instruments being of single-piece U-section hollow form from end to end and having a point at its leading end, transfer shoulders behind the said point and recesses formed in the edges of its side walls, a plate serving to secure the loop transferring instruments in the said second bar and having thereon a locating formation engaged in the aforesaid recesses, and a spacing bar interposed between and serving to connect the said second bar and the securing plate so as to produce a hollow structure having a space therein accommodating and permitting relative movement back and forth of the first mentioned bar fitted with the welt instruments, the last mentioned instruments being housed within the hollow loop transferring instruments, the first mentioned bar being movable from an advanced position in which the welt instruments are fully projected with their hooks extending in front of the points of the loop transferring instruments to another position in which the said hooks are withdrawn into and protected by the hollow bodies of the loop transferring instruments behind the points thereof, and vice versa, and the open operative ends of the loop transferring instruments being adapted to receive the hooks and sheath the heads of needles to which loops are to be transferred.

6. For a full fashioned hosiery machine, a composite welt bar device comprising, in combination, a bar having formed therein slots and a longitudinal series of holes, a series of welt instruments each formed with a relatively fine hook and a stem wider than the hook and having a down-turned tail, the said instruments being mounted in the slots in the bar and located in the bar by engagement of their down-turned tails in the aforesaid holes, a holding bar locked to the first mentioned bar to secure the welt instruments therein, the two bars together with the welt instruments constituting a unitary "hooked welt bar," an associated third bar having grooves therein, a corresponding separate series of loop transferring instruments fitted in the said grooves, each of said loop transferring instruments being of single-piece U-section hollow form from end to end and having a point at its leading end, transfer shoulders behind the said point and recesses formed in the edges of its side walls, a plate serving to secure the loop transferring instruments in the said third bar and having thereon a locating formation engaged in the aforesaid recesses, and a spacing bar interposed between and serving to connect the third bar and the securing plate so as to produce a hollow structure having a space therein accommodating and permitting relative movement back and forth of the hooked welt bar, the welt instruments being housed within the hollow loop transferring instruments, the hooked welt bar being movable from an advanced position in which the welt instruments are fully projected with their hooks extending in front of the points of the

loop transferring instruments to another position in which the said hooks are withdrawn into and protected by the hollow bodies of the loop transferring instruments behind the points thereof, and vice versa, and the open operative ends of the loop transferring instruments being adapted to receive the hooks and sheathe the heads of needles to which loops are to be transferred.

7. A welt bar device according to claim 6, 10 wherein an intermediate tapered portion is provided between the hook and the stem of each welt instrument, for the purpose herein specified.

8. A welt bar device according to claim 6, wherein the back edge of the stem of each welt instrument is recessed to receive the point of the corresponding loop transferring instrument.
